(57) CLAIM

The ornamental design for a mosquito net, as shown and described.

DESCRIPTION

FIG. 1 is a front perspective view of a mosquito net, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view.

The thin broken lines in the drawings illustrate the portions of the mosquito net, which form no part of the claimed design.

The thick broken lines representing stitching are part of the claimed design.
